CLAIM

The ornamental design for a wireless access device, as shown and described.

DESCRIPTION

FIG. 1 is a perspective view of a wireless access device incorporating our new design, viewed from above, in front of, and the left side of the device;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is bottom plan view thereof.

The broken lines in FIGS. 1-7 that are located immediately adjacent the shaded areas represent the bounds of the claimed design, while all other broken lines are directed to the environment. All of the broken lines form no part of the claimed design.
